CONTROL DEVICE

Paul S. Jackson, Rockford, Ill., assignor to Jackson Hydraulic Machine Co., Inc., Rockford, Ill., a corporation of Illinois

Application October 23, 1948, Serial No. 56,134

19 Claims. (Cl. 103—38)

1

This invention relates to control mechanisms and more particularly to a control mechanism for a reciprocating member.

It is a general object of this invention to produce a control device for a reciprocating member.

It is a more specific object of this invention to produce a device for controlling the length of stroke of a reciprocating member.

It is a further object of this invention to produce a device for controlling the stroke of a hydraulically reciprocated member where unequal volumes of fluid are moved with reciprocation in each direction.

It is a further object of this invention to produce a control device according to any of the preceding paragraphs which is readily adjustable.

Yet another object of the invention is to produce a control device having a control panel on which are located adjustable means for controlling the volume of fluid for reciprocating a member and having indicating means associated with the panel for visually indicating the setting of the adjustable means.

Another and further objects of the invention will be apparent from the following description and drawings in which:

Fig. 1 is a diagrammatic view of the control and the hydraulic circuit;

Fig. 2 is a front elevational view of the control panel with the face removed;

Fig. 3 is a section along line 3—3 of Fig. 2;

Fig. 4 is a view like Fig. 2 with the face of the panel in place;

Fig. 5 is a sectional view along line 5—5 of Fig. 4;

Fig. 6 is a detailed sectional view of the volume control for the pump; and

Fig. 7 is an elevational view of the entire control panel.

While my invention is susceptible of embodiment in many different forms, I have shown in the drawings and will herein describe in detail one such embodiment, with the understanding that the present disclosure is to be considered as an exemplification of the principle of the invention and is not intended to limit the invention to the embodiment illustrated. The scope of the invention will be pointed out in the appended claims.

For the purpose of exemplary disclosure I have chosen to describe my invention as used in conjunction with an exerciser for exercising the recoil mechanism of a gun, although it will be apparent from the disclosure that the device may be used to control the stroke of any reciprocating device.

2

Referring now to Fig. 1 of the drawings I show a reversible, variable delivery hydraulic pump 10 which may be reversed in the usual manner through energization of solenoids 11 and 12. The volume of fluid moved in either direction by the pump may be regulated by regulating means 13 and 14 which last-named means may be controlled by knobs 15 and 16 mounted upon a control panel to be later described, which panel bears an inscribed dial 17. The knobs are connected to their respective volume control devices by rotatable rods 18 and 19.

Interposed in the hydraulic circuit is a four-way hold-up valve 20 having a casing 21 and a longitudinal bore 22 in the casing. Slidably in the bore is a spool valve device 23. The valve casing is provided with three ports, 24, 25 and 26 on one side thereof and a single port 27 on the other side. The spool valve 23 is slidable longitudinally in the bore and is urged in a closing direction by spring 28. A solenoid device 29 is adapted to operate a valve mechanism 30 to permit pilot pressure to shift the valve 23 longitudinally in the casing to open position 25 against the tension of the spring 28. The bore is provided with a passage 31 connecting with annular grooves 32 and 33 and is also provided with annular grooves 34, 35 and 36. The valve 20 has but two positions, the "on" position as shown in Fig. 1 and an "off" position in which all ports are blocked.

Also located in the hydraulic circuit is a differential relief valve 40 which comprises a casing 41 having a bore 42 therein. A spool valve 43 is slidable longitudinally in the bore and urged toward movement in one direction by a spring 44. The valve 40 is provided with three ports 45, 46 and 47 on one side of the casing, a single port 48 on the other side of the casing, and a port 49 entering directly to the bore 42. A port 50 is also provided at one end of the bore for purposes to be hereinafter described.

With the parts in the position shown in Fig. 1 hydraulic fluid under pressure from the pump 10 is directed into the cylinder line conduit 51 and enters the bore 42 through the port 49. The fluid passes by the spool valve 43 and into a passage 52 in the valve 40 to conduit 53. From conduit 53 fluid is directed into a hydraulic metering motor 54 which motor is rotated by the action of fluid passing therethrough and transmits that rotation by means of shaft 55, coupling 56, and speed reducer 57, to a shaft 58 connected to a control device 59. I prefer to use a hydraulic metering motor of the type shown when my apparatus is used in the manner

illustrated wherein portability of the entire device is essential. However, where the control device is to be used with a reciprocating member which is fixed in position, for example, as on a machine tool, I may use a rack and pinion device or other motor means connected directly to the reciprocating member to rotate the shaft 58.

From the metering motor, cylinder line fluid passes into a conduit 60 and enters the port 25 of valve 20. The fluid passes along the bore 32, into the annular groove 36 and out port 26 to a conduit 61. The conduit 61 connects with a conduit 62 and thence directly into the cylinder 63 in which the reciprocating member is located to reciprocate the member in one direction. Also connected to the conduit 62 is a bleeder valve 64 and a pressure gauge 65. The conduit 62 also opens to the bore 42 of valve 40 through the port 59 and fluid pressure against the plunger 50 secured to the spool valve serves to urge the spool valve 43 to the position shown.

Removably attached to the other end of the cylinder 63 is a hydraulic jack 64 having a member adapted to bear against the rod 65 connected to the reciprocating member. It is understood that the rod 65 is normally a part of the recoil mechanism of the gun. Fluid returning from the jack 64 enters the jack line 66 in which bleeder valves 67 and pressure gauge 68 are located and passes along the conduit 69 and into the port 24 of the valve 20. The fluid thence passes along annular groove 34 into the passage 31 and thence into the conduit 70 by means of the port 27. The conduit 70 is connected to a conduit 71 which leads into the port 72 of pump 10 and also is connected to the valve 40.

As the volume of fluid pumped by the pump 10 exceeds the volume returned from the hydraulic jack 64, means are provided for making up the difference between the volumes. Accordingly, I provide a make-up pump 73 driven by the same means as drives the pump 10 and make-up fluid is supplied into the conduit 74 having a pressure gauge 75 connected therewith and thence into the valve mechanism 30 for shifting the spool valve 23 in accordance with the position of the solenoid 29. Make-up fluid is also supplied directly to the conduit 76 which is connected to a conduit 77 and port 47 of valve 40. With the valve in the position shown, make-up fluid may enter the port 47, pass along the annular groove 77 and bore 42 and into the conduit 71 through the port 46.

When the reciprocating member in the cylinder 63 reaches the end of its stroke my control device hereinafter to be explained serves to reverse the pump 10. With the pump 10 reversed, fluid under pressure reverses its direction in the line 71 and passes through the means just described into the jack line 66. Fluid returning from the cylinder line through conduit 62 reverses its direction through the valve 20 and the metering motor 54 to rotate the motor the same number of revolutions as when the circuits were reversed, but in the opposite direction. As suction is applied to the line 62 the spool 43 of valve 40 is shifted upward (as shown in Fig. 1) to block off ports 46 and 47 and prevent jack line pressure from the pump 10 from entering the make-up circuit. Port 49 is also blocked and port 45 is connected with the passage 52 so that all hydraulic fluid returning from cylinder 63 through valve 20 and motor 54 in line 53 is directed through port 45, 52 and bore 42 to port 45 into the conduit 80 connected to

the tank or sump. With the valve 40 in this position, pump suction is through a pipe and check valve (not shown), but incorporated in the pump.

My control device contemplates means for energizing the solenoids 11 and 12 to reverse pump 10 when the reciprocating member in the cylinder 63 reaches the end of its stroke in each direction. Accordingly, the shaft 58 which is rotated by the metering motor is mounted in a housing 81 and terminates in a reduced portion 82 extending beyond the face of a dial 83. A hollow shaft 84 is frictionally secured to the portion 82 and similarly extends beyond the face of the dial 83 and terminates in a knob-like portion 85. A spring 86 is positioned between a shoulder portion 87 of the knob 85 and a cap 88 on the end of the shaft 82 to urge the shaft 84 and 82 to rotate together. The spring just described constitutes a part of a clutch member whereby the shaft 84 may be rotated independent of the rotation of the shaft 82.

Fixed to the shaft 84 is a spur gear 89 meshing with a second spur gear 90 fixed upon a control shaft 91 rotatably mounted in the housing 81. The control shaft 91 is mounted in bearings 92 and 93 and is urged toward downward movement (as shown in Fig. 3) by a spring 94, the downward movement causing an extension 95 of the gear 90 to bear against the end of a collar portion 96 secured in the housing. A pointer 97 is secured to the outer end of the control shaft 91 and exterior to the panel 83.

Rotatably mounted on the collar portion 96 is a spur gear 98 which meshes with an idler gear 99 mounted upon shaft 100 in the housing. The idler gear 99 meshes with a gear 101 mounted upon shaft 102. The shaft 102 is rotatably mounted in the housing and carries a second gear 103 meshing with an internal gear 104 rotatably mounted in the housing 81. The internal gear carries a pointer 105 which is moved with rotation of the gear 104 across the face of the dial panel. The dial 83 is suitably inscribed with figures indicating the number of cubic inches of fluid necessary to effect reciprocation of the member and rotation of the gear 104 is adapted to move the pointer 105 across the inscribed face of the dial visually to indicate the volume of fluid to be pumped at any particular setting of the pointer. A control knob 106 is mounted upon the end of the shaft 102 and may be manually rotated to rotate the internal gear 104 and the spur gear 98.

A control arm 110 is rigidly fixed to the control shaft 91 and oscillated with reversing rotation of the shaft 91. The outer end of the control arm carries a bearing 111 adapted to depress a limit switch 112 mounted in the housing to energize one of the solenoids and effect reversal of the pump 10. The spur gear 98 is provided with a device in the form of a bolt 113 which extends into the path of oscillation of the control arm 110. Reversal of the pump by contact 65 of the control arm 110 with the limit switch 112 causes the control arm to oscillate in the opposite direction and bring the bearing 111 into contact with the device 113. Such a contact serves to move the control shaft 91 longitudinally of its axis of rotation and against a second limit switch 114 to energize the other solenoid and again to reverse the pump 10.

The position of the device 113 in the path of oscillation of the control arm is, of course, dependent upon the position of the gear 98 and

the gear may be rotated by means of the knob 106 through the gears 101 and 99, as previously described.

Actuation of the limit switch 114 can be performed manually at any time by inward pressure of the pointer 97 to reverse the motor 10.

It is clear that by rotation of the knob 106 the pointer 105 is moved along the scale of the dial until the desired volume of flow in the cylinder line is indicated, the volume, of course, being determined by the volume of fluid necessary to reciprocate the device in the cylinder 63 through a full stroke in one direction. Simultaneously with movement of the pointer 105 the device 113 is moved either toward or away from the limit switch 112 in the plane of the path of oscillation of the control arm 110 to determine the amount of oscillation of that arm necessary to effect successive reversal of the pump. The actual speed of reciprocation of the member and cylinder 63 is, of course, determined by the setting of the volume controls on the pump 10 but regardless of the speed of reciprocation my control device serves to effect reversal of the pump at the desired point in the stroke of the reciprocating member.

The inscribed dials 17 and 83 are mounted upon a control panel 120 which also carries the gauges 65, 68 and 75 and knobs 15, 16, 85 and 106. The shafts 18 and 19 are rotatably mounted on the panel, the rod 18 being connected directly to the volume control 13 while the rod 19 is connected to the volume control 14 through a series of spur gears 121, 122 and 123 rotatably mounted in housing 124. Secured to the control panel 120 is a housing 125 in which a pair of ring gears 126 and 127 are rotatably mounted, the ring gear 126 meshing with a spur gear 128 fixed to the shaft 18 and the ring gear 127 meshing with a spur gear 129 fixed to the shaft 19. The ring gear 127 carries a pointer 130 movable around the dial 17 and the ring gear 127 carries a second pointer 131 similarly movable around the dial. Rotation of the knob 15 which, for example, may be the volume control for the cylinder line, serves through the gears just mentioned not only to control the operation of the volume control 13 but also to move the pointer 131 over the inscribed face of the dial 17 to indicate the volume of fluid moved by the pump in one direction. The pointer 130 associated with the jack line control indicates the volume moved by the pump through the jack line.

I claim:

1. A stroke-control apparatus for a reciprocable member comprising reversible means for reciprocating the member, means for reversing the reversible means, a motor driven in forward and reverse in synchronism with the reciprocation of the member, a control shaft oscillated by the motor, actuating means for the reversing means, means for operating the actuating means carried by the control shaft and adapted to operate the actuating means at the end of an oscillation of the control shaft in one direction to reverse the reciprocating means, a device extending into the path of oscillation of the operating means in the other direction and adapted to operate the operating means upon contact with the operating means again to reverse the reciprocating means, and manually operable setting means for selectively moving the device to various points in the path of oscillation of the operating means.

2. A stroke-control apparatus for a reciprocable member comprising reversible means for recipro-

cating the member, means for reversing the reversible means, a motor driven in forward and reverse in synchronism with the reciprocation of the member, a control shaft oscillated by the motor, actuating means for the reversing means, means for operating the actuating means carried by the control shaft and adapted to operate the actuating means at the end of an oscillation of the control shaft in one direction to reverse the reciprocating means, a device extending into the path of oscillation of the operating means in the other direction and adapted to operate the operating means upon contact therewith again to reverse the reciprocating means, manually operable setting means for selectively locating the device at various points in the path of oscillation of the operating means and manually operable means for oscillating the control shaft independent of the motor.

3. A stroke-control apparatus for a reciprocable member comprising reversible means for reciprocating the member, means for reversing the reversible means, a motor driven in forward and reverse in synchronism with the reciprocation of the member, a control shaft oscillated by the motor, actuating means for the reversing means, means for operating the actuating means carried by the control shaft and adapted to operate the actuating means at the end of an oscillation of the control shaft in one direction to reverse the reciprocating means, a device extending into the path of oscillation of the operating means in the other direction and adapted to operate the operating means upon contact therewith again to reverse the reciprocating means, manually operable setting means for selectively moving the device to various points in the path of oscillation of the operating means, a graduated control panel, and indicating means operated by the setting means to indicate on the panel the location of the device.

4. A stroke-control apparatus for a reciprocable member comprising reversible means for reciprocating the member, means for reversing the reversible means, a motor driven in forward and reverse in synchronism with the reciprocation of the member, a control shaft oscillated by the motor, actuating means for the reversing means, means for operating the actuating means carried by the control shaft and adapted to operate the actuating means at the end of an oscillation of the control shaft in one direction to reverse the reciprocating means, a device extending into the path of oscillation of the operating means in the other direction and adapted to operate the operating means upon contact therewith again to reverse the reciprocating means, manually operable setting means for selectively moving the device to various points in the path of oscillation of the operating means, a graduated control panel, indicating means operated by the setting means to indicate on the panel the location of the device, a pointer on the panel aligned with the operating means and oscillated by the control shaft to indicate on the panel the position of the operating means.

5. A stroke-control apparatus for a reciprocable member comprising reversible means for reciprocating the member, means for reversing the reversible means, a motor driven in forward and reverse in synchronism with the reciprocation of the member, a control shaft oscillated by the motor, actuating means for the reversing means, means for operating the actuating means carried by the control shaft and adapted to operate the

actuating means at the end of an oscillation of the control shaft in one direction to reverse the reciprocating means, a device extending into the path of oscillation of the operating means in the other direction and adapted to operate the operating means upon contact therewith again to reverse the reciprocating means, manually operable setting means for selectively moving the device to various points in the path of oscillation of the operating means, a graduated control panel, indicating means operated by the setting means to indicate on the panel the location of the device, a pointer on the panel aligned with the operating means and oscillated by the control shaft to indicate on the panel the position of the operating means, and manually operable means on the panel for oscillating the control shaft independent of the motor.

6. A stroke-control apparatus for a reciprocable member comprising reversible means for reciprocating the member, means for reversing the reversible means, a motor driven in forward and reverse in synchronism with the reciprocation of the member, a control shaft oscillated by the motor, actuating means for the reversing means, means for operating the actuating means carried by the control shaft and adapted to operate the actuating means at the end of an oscillation of the control shaft in one direction to reverse the reciprocating means, a device extending into the path of oscillation of the operating means in the other direction and adapted to operate the operating means upon contact therewith again to reverse the reciprocating means, manually operable setting means for selectively moving the device to various points in the path of oscillation of the operating means, a graduated control panel, a pointer movable around the panel, a knob on the panel mounted on a rotatable setting shaft, a first gear on the setting shaft for moving the pointer and a second gear on the setting shaft for moving the device to various points in said path.

7. A stroke-control apparatus for a reciprocable member comprising reversible means for reciprocating the member, means for reversing the reversible means, a motor driven in forward and reverse in synchronism with the reciprocation of the member, a control shaft oscillated by the motor, actuating means for the reversing means, means for operating the actuating means carried by the control shaft and adapted to operate the actuating means at the end of an oscillation of the control shaft in one direction to reverse the reciprocating means, a rotatably mounted gear, a device mounted on the rotatable gear and extending into the path of oscillation of the operating means in the other direction and adapted to operate the operating means upon contact therewith again to reverse the reciprocating means, a graduated control panel, a pointer mounted on an internally toothed gear and movable around the panel, a knob on the panel mounted on a rotatable setting shaft, a first gear on the setting shaft meshing with the internal gear and a second gear on the shaft for rotating the gear carrying the device.

8. In combination with a reciprocable member and electrically reversible means for reciprocating the member, a control device for the reciprocating means comprising a housing, a control shaft rotatably mounted in the housing and oscillated in synchronism with reciprocation of the member, a pair of limit switches in the housing for reversing the reciprocating means, a control arm carried by the shaft and adapted to operate one

5 of said switches at the end of an oscillation of the control arm in one direction, a device extending into the path of oscillation of the control arm in the other direction and adapted to cause operation of the other switch upon contact of the control arm therewith, and manually operable setting means for selectively moving the device to various points in the path of oscillation of the control arm.

9. In combination with a reciprocable member and electrically reversible means for reciprocating the member, a control device for the reciprocating means comprising a housing, a control shaft rotatably mounted in the housing and oscillated in synchronism with reciprocation of the member, a pair of limit switches in the housing for reversing the reciprocating means, a control arm carried by the shaft and adapted to operate one of said switches at the end of an oscillation of the control arm in one direction, a gear in the housing rotatably mounted about the axis of rotation of the control shaft, a device carried by the gear and extending into the path of oscillation of the control arm in the other direction and adapted to cause operation of the other switch upon contact of control arm therewith, a setting shaft rotatably mounted in the housing, and a gear mounted on the setting shaft for rotating the gear carrying the device for selectively moving the device to various points in the path of oscillation of the control arm.

10. In combination with a reciprocable member and electrically reversible means for reciprocating the member, a control device for the reciprocating means comprising a housing, a control shaft rotatably mounted in the housing and oscillated in synchronism with reciprocation of the member, a pair of limit switches in the housing for reversing the reciprocating means, a control arm carried by the shaft and adapted to operate one of said switches at the end of an oscillation of the control arm in one direction, a gear in the housing rotatably mounted about the axis of rotation of the control shaft, a device carried by the gear and extending into the path of oscillation of the control arm in the other direction and adapted to cause operation of the other switch upon contact of the control arm therewith, a graduated control panel on the housing, a pointer movable around the panel and carried by an internally toothed gear rotatably mounted in the housing, a knob on the panel and mounted on a rotatable setting shaft, a first gear on the setting shaft meshing with the internally toothed gear, and a second gear on the setting shaft for rotating the gear carrying the device, rotation of the knob being adapted to move the device to various points in the path of oscillation of the control arm and simultaneously to move the pointer around the panel.

11. In combination with a reciprocable member and electrically reversible means for reciprocating the member, a control device for the reciprocating means comprising a housing, a control shaft rotatably mounted in the housing, means for oscillating the control shaft in synchronism with reciprocation of the member, a pair of limit switches in the housing for reversing the reciprocating means, a control arm carried by the shaft and adapted to operate one of said switches at the end of an oscillation of the control arm in one direction, a gear in the housing rotatably mounted about the axis of rotation of the control shaft, a device carried by the gear and extending into the path of oscillation of the control arm in the

other direction and adapted to cause operation of the other switch upon contact of the control arm therewith, a graduated control panel on the housing, a pointer movable around the panel and carried by an internally toothed gear rotatably mounted in the housing, a knob on the panel mounted on a rotatable setting shaft, a first gear on the setting shaft meshing with the internally toothed gear, a second gear on the setting shaft for rotating the gear carrying the device, rotation of said setting shaft being adapted to move the device to various points in the path of oscillation of the control arm and to move the pointer around the panel, a drive shaft interposed between the oscillating means and the control shaft and clutch means for rotating the drive shaft to oscillate the control shaft independent of the oscillating means.

12. In combination with a reciprocable member and electrically reversible means for reciprocating the member, a control device for the reciprocating means comprising a housing, a control shaft rotatably mounted in the housing and movable therein longitudinally of its axis of rotation, means urging the control shaft toward movement in one longitudinal direction, means for oscillating the control shaft in synchronism with reciprocation of the member, a pair of limit switches in the housing for reversing the reciprocating means, a control arm carried by the shaft and adapted to contact one of the said switches at the end of an oscillation of the control arm in one direction, a device extending into the path of oscillation of the control arm in the other direction and adapted to contact the control arm to move the shaft longitudinally in the housing in the other direction and into operating contact with the other switch, a graduated control panel on the housing, a pointer movable around the panel and carried by an internally toothed gear rotatably mounted in the housing, a knob on the panel and mounted on a rotatable setting shaft, a first gear on the setting shaft meshing with the internally toothed gear, a second gear on the setting shaft, an idler gear meshing with the second gear and meshing with the gear carrying the device, rotation of said setting shaft being adapted to move the device to various points in the path of oscillation of the control arm and to move the pointer about the panel.

13. In a combination with a reciprocable member and electrically reversible means for reciprocating the member, a control device for the reciprocating means comprising a housing, a control shaft rotatably mounted in the housing and movable therein longitudinally of its axis of rotation, means urging the control shaft toward movement in one longitudinal direction, means for oscillating the control shaft in synchronism with reciprocation of the member, a pair of limit switches in the housing for reversing the reciprocating means, a control arm carried by the shaft and adapted to contact one of the said switches at the end of an oscillation of the control arm in one direction, a device extending into the path of oscillation of the control arm in the other direction and adapted to contact the control arm to move the shaft longitudinally in the housing in the other direction and into operating contact with the other switch, a graduated control panel on the housing, a pointer movable around the panel and carried by an internally toothed gear rotatably mounted in the housing, a knob on the panel and mounted on a rotatable setting shaft, a first gear on the setting shaft meshing

with the internally toothed gear, a second gear on the setting shaft, an idler gear meshing with the second gear and meshing with the gear carrying the device, rotation of said setting shaft being adapted to move the device to various points in the path of oscillation of the control arm and to move the pointer about the panel, a drive shaft interposed between the oscillating means and the control shaft and geared to the control shaft and clutch means on the control panel for rotating the drive shaft to oscillate the control shaft independent of the oscillating means.

14. In combination with a reciprocable member and electrically reversible means for reciprocating the member, a control device for the reciprocating means comprising a housing, a control shaft rotatably mounted in the housing and movable therein longitudinally of its axis of rotation, means urging the control shaft toward movement in one longitudinal direction, means for oscillating the control shaft in synchronism with reciprocation of the member, a pair of limit switches in the housing for reversing the reciprocating means, a control arm carried by the shaft and adapted to contact one of the said switches at the end of an oscillation of the control shaft in one direction, a device extending into the path of oscillation of the control arm in the other direction and adapted to contact the control arm to move the shaft longitudinally in the housing in the other direction and into operating contact with the other switch, a graduated control panel on the housing, a pointer movable around the panel and carried by an internally toothed gear rotatably mounted in the housing, a knob on the panel and mounted on a rotatable setting shaft, a first gear on the setting shaft meshing with the internally toothed gear, a second gear on the setting shaft, an idler gear meshing with the second gear and meshing with the gear carrying the device, rotation of said setting shaft being adapted to move the device to various points in the path of oscillation of the control arm and to move the pointer about the panel, and a second pointer on the panel mounted on the end of the control shaft and aligned with the operating means to indicate on the panel the position of the operating means, manual pressure on said second pointer being adapted to move the control shaft longitudinally against the urging means to operate said other switch.

15. In a hydraulic circuit including a reversible pump and means for controlling the volume of fluid moved by the pump in forward and in reverse, a control comprising a control panel, a graduated dial on the panel, pointers movable around the dial, a knob rotatably mounted on the panel and connected to a pointer and to one of the volume control means, a second knob rotatably mounted on the panel and connected to another pointer and to the other volume control means, rotation of a knob being adapted to operate a volume control means and to move a pointer on the dial, a second graduated dial on the panel, a third pointer movable around the second dial, adjustable means mounted on the panel for reversing the pump and a third knob rotatably mounted on the panel and connected to the third pointer and to the reversing means, rotation of the third knob being adapted to move the reversing means for controlling the operation thereof and to move the third pointer on the second dial.

16. In a hydraulic circuit including a reversible pump, a control comprising a control panel, a graduated dial on the panel, a pair of ring

gears rotatably mounted on the panel concentric with the dial, a pointer on each gear and movable around the dial, a pair of shafts rotatably mounted on the panel, a spur gear on each shaft meshing with a different one of said ring gears, means for controlling the volume of fluid moved by the pump in forward and means for controlling the volume of fluid moved by the pump in reverse, each of said shafts being connected to a different one of said volume control means, whereby rotation of each of said shafts is adapted to operate the volume control means connected thereto and to move a pointer around the dial.

17. In a hydraulic circuit including a reversible pump, a control comprising a control panel, a graduated dial on the panel, a pair of ring gears rotatably mounted on the panel concentric with the dial, a pointer on each ring gear and movable around the dial, a pair of shafts rotatably mounted on the panel, a spur gear on each shaft meshing with a different one of said ring gears, means for controlling the volume of fluid moved by the pump in forward and means for controlling the volume of fluid moved by the pump in reverse, each of said shafts being connected to a different one of said volume control means, whereby rotation of each of said shafts is adapted to operate the control means connected thereto and to move a pointer around the dial, a second graduated dial on the panel, a third pointer movable around the second dial, a first gear carrying the third pointer, adjustable means for reversing the pump, a second gear for adjusting the reversing means, a third shaft rotatably mounted on the panel, a third gear carried by the third shaft and meshing with the second gear, a fourth gear on the third shaft meshing with the first gear carrying the third pointer, whereby rotation of said third shaft is adapted to adjust the reversing means and to move the third pointer on the second dial.

18. In a hydraulic circuit including a reversible pump, and a metering motor driven by the pump, a control comprising a control panel, a graduated dial on the panel, a pair of ring gears rotatably mounted on the panel concentric with the dial, a pointer on each gear and movable around the dial, a pair of shafts rotatably mounted on the panel, a spur gear on each shaft meshing with a different one of said ring gears, means for controlling the volume of fluid moved by the pump in forward and means for controlling the volume of fluid moved by the pump in reverse, each of said shafts being connected to a volume control means, whereby rotation of said shafts is adapted to operate the volume control means connected thereto and to move a pointer around the dial, a second graduated dial on the panel, a third pointer movable around the second dial, a control shaft oscillated by the motor, a control arm mounted on the control shaft and carrying means for reversing the pump,

an externally toothed gear rotatably mounted on the panel, means for operating the reversing means carried by the last-mentioned gear, an internally toothed gear rotatably mounted on the panel and carrying the third pointer, a third shaft rotatably mounted on the panel and carrying a first gear meshing with the externally toothed gear and carrying a second gear meshing with the internally toothed gear, whereby rotation of said shaft is adapted to move the operating means and to move the third pointer on the second dial.

19. In a hydraulic circuit including a reversible pump, and a metering motor driven by the pump, a control comprising a control panel, a graduated dial on the panel, a pair of ring gears rotatably mounted on the panel concentric with the dial, a pointer on each gear and movable around the dial, a pair of shafts rotatably mounted on the panel, a spur gear on each shaft meshing with a different one of said ring gears, means for controlling the volume of fluid moved by the pump in forward and means for controlling the volume of fluid moved by the pump in reverse, each of said shafts being connected to a different one of said volume control means, whereby rotation of said shafts is adapted to operate the volume control means connected thereto and to move a pointer around the dial, a second graduated dial on the panel, a third pointer movable around the second dial, a control shaft oscillated by the motor, a control arm mounted on the control shaft and carrying means for reversing the pump, an externally toothed gear rotatably mounted on the panel, means for operating the reversing means carried by the last-mentioned gear, an internally toothed gear rotatably mounted on the panel and carrying the third pointer, a shaft rotatably mounted on the panel, a first gear on the last-mentioned shaft meshing with the externally toothed gear, a second gear on the last-mentioned shaft meshing with the internally toothed gear, rotation of said last-mentioned shaft being adapted to move the operating means and to move the third pointer on the second dial, a second shaft rotatably mounted on the panel and connecting the control shaft with the motor and means for rotating the second shaft to oscillate the control arm independent of the motor.

PAUL S. JACKSON.
